UNITED STATES PATENT OFFICE.

JOSEPH D. COSSETTE, OF ESCANABA, MICHIGAN.

DESIGN FOR A SHINGLING-TOOL.

45,687.

Specification for Design.

Patented Apr. 28, 1914.

Application filed February 28, 1914. Serial No. 821,805. Term of patent 14 years.

To all whom it may concern:

Be it known that I, JOSEPH D. COSSETTE, a citizen of the United States, residing at Escanaba, in the county of Delta and State of Michigan, have invented a new, original, and ornamental Design for a Shingling-Tool, of which the following is a specification, reference being had to the accompanying drawing, forming part thereof.

The figure is a perspective view of the tool, showing my new design.

I claim:

The ornamental design for a shingling tool, as shown.

JOSEPH D. COSSETTE.

Witnesses:

EMIL GLASER,

GEORGE McCARTHY.
